US00D840539S

(12) **United States Design Patent** (10) **Patent No.:** **US D840,539 S**
(45) **Date of Patent:** **** Feb. 12, 2019**

(54) **PROSTHESIS ANCHOR**

(71) Applicant: **TORNIER, INC.**, Bloomington, MN (US)

(72) Inventors: **Robert Courtney**, Pierceton, IN (US); **Austin W. Mutchler**, Warsaw, IN (US); **Jeffrey M. Ondrla**, Warsaw, IN (US)

(73) Assignee: **Tornier, Inc.**, Bloomington, MN (US)

(**) Term: **15 Years**

(21) Appl. No.: **29/544,231**

(22) Filed: **Oct. 30, 2015**

Related U.S. Application Data

(62) Division of application No. 29/456,077, filed on May 28, 2013, which is a division of application No. (Continued)

CLAIM

The ornamental design for prosthesis anchor, as shown and described.

DESCRIPTION

FIG. 1 is a top perspective view of an embodiment; FIG. 2 is a bottom perspective view of the embodiment of FIG. 1;

FIG. 3 is a front view of the embodiment of FIG. 1;

FIG. 4 is a back view of the embodiment of FIG. 1;

FIG. 5 is a left side view of the embodiment of FIG. 1;

FIG. 6 is a right side view of the embodiment of FIG. 1;

FIG. 7 is a top view of the embodiment of FIG. 1; and

FIG. 8 is a bottom view of the embodiment of FIG. 1.

FIG. 9 is a top perspective view of another embodiment;

FIG. 10 is a bottom perspective view of the embodiment of FIG. 9;

FIG. 11 is a front view of the embodiment of FIG. 9;

FIG. 12 is a back view of the embodiment of FIG. 9;

FIG. 13 is a left side view of the embodiment of FIG. 9;

FIG. 14 is a right side view of the embodiment of FIG. 9;

FIG. 15 is a top view of the embodiment of FIG. 9; and

FIG. 16 is a bottom view of the embodiment of FIG. 9.

FIG. 17 is a top perspective view of another embodiment;

FIG. 18 is a bottom perspective view of the embodiment of FIG. 17;

FIG. 19 is a front view of the embodiment of FIG. 17;

FIG. 20 is a back view of the embodiment of FIG. 17;

FIG. 21 is a left side view of the embodiment of FIG. 17;

FIG. 22 is a right side view of the embodiment of FIG. 17;

FIG. 23 is a top view of the embodiment of FIG. 17; and,

FIG. 24 is a bottom view of the embodiment of FIG. 17.

The broken line showing is included for the purpose of illustrating boundary lines and unclaimed subject matter and forms no part of the claimed design.

1 Claim, 24 Drawing Sheets
